U.S. Appl. No. 29/371,159, Nathan et al., filed Nov. 2, 2010.

Primary Examiner — Prabhakar Deshmukh*(74) Attorney, Agent, or Firm* — Nixon & Vanderhye PC**(57) CLAIM**

The ornamental design for a speaker array for a jukebox, as shown and described.

DESCRIPTION

FIG. 1 is a front perspective view of a speaker array for a jukebox showing our new design;

FIG. 2 is a front elevation view thereof; and,

FIG. 3 is a right side elevation view thereof, the left side elevation view being a mirror image thereof.

The dashed lines shown represent environmental structure and form no part of the claimed design.
